INVENTOR

UNITED STATES PATENT OFFICE.

THOMAS M. BURGESS, OF BIG RAPIDS, MICHIGAN.

CURTAIN-FIXTURE.

SPECIFICATION forming part of Letters Patent No. 251,762, dated January 3, 1882.

Application filed August 6, 1880. (No model.)

To all whom it may concern:

Be it known that I, THOMAS MAYOR BURGESS, a citizen of the United States, resident at Big Rapids, in the county of Mecosta and State of Michigan, have invented certain new and useful Improvements in Curtain-Fixtures; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to curtain-fixtures; and the novelty consists in the construction and arrangement of parts, as will be hereinafter more fully set forth, and particularly pointed out in the claim.

20 Figure 1 of the drawings is a representation of a front elevation of a window-frame, showing my improvements applied with the curtain partly lowered, and Fig. 2 is a transverse sectional view of the same. Fig. 3 is a view of the strip or bar *c*, showing the brackets applied.

The letter *A* of the drawings represents a window-frame of any ordinary construction, to the sides of which are secured strips of wood 30 or other suitable material (marked *B B*) having longitudinal grooves *b b* to receive the ends of the wooden strip or stick *O* at the lower end of the curtain, which prevents the said curtain from being blown in and out by the wind through the window.

The letter *C* represents a strip or bar, which is suspended by means of cords in the grooves of the said vertical strips *B*, and carries brackets which form bearings for the curtain-roller. 40 This strip *C* has staples *cc* upon its upper edge and near its outer ends, to which are fastened cords *d* and *d'*, and by which the strip is suspended in the grooves *b* of the vertical strips. These cords, (marked *d* and *d'*), after being fastened to the staples *cc* of the strip *C*, are carried upward through guides or rings *f'*, which are secured near the top of the window-frame, and the cord *d'* carried horizontally across the window-frame to the cord *d*, passed through 45 the guide *f'* with the cord *d'*, and both carried down the side of the window-frame to spring-

55 catch, where they are fastened within reach of the operator.

The strip *C* has brackets *D D*, made of wire, as shown, secured to the said strip by screws or otherwise, to furnish bearings for the curtain-roller.

60 The letter *E* represents the curtain, the roller *F* of which is made of wood, and to both ends of which are secured metallic collars *E* and *E''*, which are placed in the brackets on the strip *C*. Upon one end of the curtain-roller is a winding-drum, *g*, having a cap, *g'*, upon its outer end, with a hole through which the curtain-string is passed and secured by a knot or otherwise.

65 To operate the curtain the operator should grasp the cords upon the left-hand side of the window-frame, release the same from the spring-catch, and by slackening the cords the strip *C*, carrying the window-curtain, will slide down in the grooves of the said vertical strips *B*. By pulling downward upon the said cords and fastening them to the spring-catch the curtain may be held in the grooves in the vertical strips in the window-frame at any desired 70 height. The curtain is not rolled upon its roller by operating these cords *d* and *d'*, but is merely raised and lowered in the grooves *b* of the vertical strips *B* on the window-frame. 75 The cord *H* upon the winding-drum is used to roll the curtain upon its roller.

80 The stick at the bottom of the curtain should be sufficiently heavy to bear the curtain down in the vertical grooves when the cord fastened to the winding-drum is slackened or released 85 from the spring-catch.

If desired, the vertical strips on the sides of the window-frame may be dispensed with and the frame grooved to receive the ends of the strips *C* and *G*.

I am aware that curtains have been made with bottom strips having guide-eyes, through which stay-cords pass, and also made with strips the ends of which extend into grooves in the frame at the sides. I am also aware that curtains have been provided with cords, so that they may be raised or lowered and held at various positions. Hence I do not claim these different features, but simply the improvement I have shown and hereinafter claimed.

Having thus fully described my invention,

what I claim as new, and desire to secure by Letters Patent of the United States, is—

The curtain E, having strips C and O, in combination with strips B, having grooves *b*,
5 the ends of the strips traveling in the grooves, roller F', having drum *g*, and cords for winding up and for lifting the curtain, whereby the curtain can be raised or lowered and is kept steady at any position, as set forth.

In testimony whereof I affix my signature to in presence of two witnesses.

THOMAS MAYOR BURGESS.
